W. P. Cresson, David Stuart, Samuel H. Sailor & Jacob Beesley (Affigmas of W. P. Cresson) County of Philad. Pa., Letters Patent (Design No. 117) dated 17 April 1847.

The schedule referred to in these Letters Patent and making part of the same.

To all whom it may concern Be it known that Wm. P. Cresson, David Stuart, Samuel H. Sailor & Jacob Beesley all of the County of Philad^a in the State of Pennsylvania have invented a new and useful set of Designs to ornament a Parlour Coal Stove and they may be used to ornament a variety of stoves and do hereby declare that the following is in connection with the accompanying drawings a full and exact description of the particular plates which we wish to Patent.

The general form of the stove as now laid out is a square formed box for the ash top surmounted with a circular ornamented cast iron screen or net-work intended to cover a common cast-iron cylinder which usually contains the coal, at the top of which is an ornamental ring or top above which is a sheet iron drum which is again surmounted with an ornamental cast iron top. The whole stove is in the general form of a stone called the cannon stone. But these ornamental designs may be laid out on stoves of any variety of form.

Plate 1 Represents the hearth or bottom plate of the stove it consists of the square which forms the ash box which is ornamented by a series of scroll and leaf work as at a a a a the plate is elongated by the hearth which is ornamented by two pheasant heads at either side each holding a sprig in its beak see b.b.

The ornament is continued around the side edges to the centre of the front edge which is beautifully ornamented with a tuft of leaf work see c.

Plate 2 Represents the top plate of the ash box it is surrounded with the same scroll and leaf work which surrounds the square part of the hearth plate see a a a a each corner is ornamented with a rosette of leaf work see b.b.b.b. In near connection with the ornaments above described is a collar intended to receive the cylindrical body of the stove and is ornamented with a wreath of leaves and berries see c c c c.

Plate 3. Fig 1. Is intended to represent the side plate of the ash box as well as the back of the same. The center of which is ornamented with a pheasant head which holds in its beak a twig of leaves and flowers. its neck is ornamented with a wreath of leaves from underneath of which also extend other leaves which spread over nearly the whole plate, the top and bottom edges of the plate are ornamented with a line of leaves and berries same as enriching the collar of the top plate in plate 2.

Fig 2 Represents the drawer front, the center is ornamented with leaf and scroll work see a a a a the edges is ornamented with a line of leaf and berry wreath work.

Fig 3 Represents the front plate intended to receive the ash dinner is ornamented along the top edge with the maker's name surrounded partially with the wreath of berry and leaf work.

Fig. 4 Represents the corner pieces of which there are 4 intended to cover the joints of the corners of the ash box it is ornamented with leaves extending up from the center of this plate or extreme corner of the stone to the edge of the plate see a a a

Fig. 5. Represents the open screen work or net work immediately above the ash box and surrounding the coal cylinder, there are 4 of these plates to this stone together they form a circle the edges top and bottom of each plate are ornamented with a line of leaf and berry and leaf work which together encircle the stone, from near the bottom left hand corner is seen the sweet stems of a boquet of flowers which extend themselves over the remainder of the plate to say between the upper and lower wreaths of berry and leaf work

screen and coal cylinder it is ornamented by a succession of scrolls and leaf work entirely around it. see a a a

Fig. 7 Represents the top ring over the sheet iron work it is ornamented with a succession of leaf and scroll work entirely around the outer edge of open work within which is another wreath of leaves or flowers.

We have thus described the particular Ornamental Designs of each plate, and do hereby claim the exclusive right to the design as a whole as we have laid them out on this particular stone.
We also claim the exclusive right to the following particular ornament; The whole of the ornaments around the stone plate on Plate 1 and on the edge of Plate No. 2, also the rosettes in the corners of Plate 2 and the Boquet ornamenting fig 5 Plate 3 and fig 6 & 7 of 6 Plate No 3.
